A. E. DRUMMOND.
LADDER EXTENSION.
APPLICATION FILED MAY 7, 1917.

1,251,192.

Patented Dec. 25, 1917.

UNITED STATES PATENT OFFICE.

ABRAHAM E. DRUMMOND, OF STAUNTON, VIRGINIA.

LADDER EXTENSION.

1,251,192.

Specification of Letters Patent. Patented Dec. 25, 1917.

Application filed May 7, 1917. Serial No. 167,109.

To all whom it may concern:

Be it known that I, ABRAHAM E. DRUMMOND, a citizen of the United States, residing at Staunton, in the county of Augusta 5 and State of Virginia, have invented certain new and useful Improvements in Ladder Extensions; and I do declare the following to be a full, clear, and exact description of the invention, such as will enable others 10 skilled in the art to which it appertains to make and use the same.

My invention relates to that class of devices intended for extending either leg of a ladder so that the same may stand vertically 15 on inclined surfaces.

I am aware that devices for this purpose have heretofore been devised, but they have been more or less cumbersome and often prone to slip after adjustment, thus often 20 causing the ladder and the person thereon to fall. The principal object, therefore, is to provide a simple and inexpensive device which will be very effective, there being no possibility whatever of the extension leg 25 slipping after it is once adjusted.

Another object is to provide a device of the class described which will be applicable to ordinary ladders without changing the construction thereof in any way.

30 Yet another object is to provide an extension leg which may be used on either leg of the ladder.

With the foregoing general objects in view, the invention resides in the novel features of construction and unique combinations of parts to be hereinafter fully described and claimed, the descriptive matter being supplemented by the accompanying drawing which constitutes a part of this application and in which:

Figure 1 is a side elevation of a ladder, showing the application of the invention;

Fig. 2 is an edge view of Fig. 1;

Fig. 3 is a vertical section through the attachment on the plane of the line 3—3 of Fig. 2;

Figs. 4 and 5 are horizontal sections on the planes of the lines 4—4 and 5—5 respectively of Fig. 2;

50 Figs. 6 and 7 are horizontal sectional views on the planes indicated by the lines 6—6 and 7—7 of Fig. 3.

In the drawings above briefly described, the numerals 1 designate the legs of a common type of ladder, the usual rounds or rungs 2 being provided between said legs.

It often occurs that the ladder must be used on inclined or irregular surfaces so that the lower ends of both legs do not rest solidly, and in order to overcome the defect, an extension leg 3 is provided, the present invention consisting in the manner of attaching said leg and securing the same in adjusted position.

A channel-iron bar 4 is provided, in the upper end of its closed side, with a vertical notch 5 while the lower end of said bar is equipped with a socket 6 to receive the lower end of either leg of the ladder, said socket being formed by a rectangular band 7 passing around the lower end of the bar 4 and spaced from the body portion thereof, said band being riveted or otherwise secured in place and having on its lower edge a flange 8 which is bent to a horizontal position to form the bottom of the socket. When either ladder leg is received in the socket 6, the upper end of the channel bar 4 is held in place by a bolt or the like 9 preferably having a wing nut 10, one bolt being in most cases provided for each leg. The bolts 9 preferably pass through washers 11 inset in the outer sides of the legs 1 as illustrated in Fig. 3.

The extension legs 3 are received slidably in the channel-bars 4 and at their lower ends are held against lateral displacement by the bands 7, the upper ends of said extension legs, however, being secured in place by means of a pair of locking bolts 12 having reduced outer ends 13 for reception in vertically spaced openings 14 formed in the side flanges of the channel bar 4. The bolts 12 are received in alined tubular guides 15 formed by bending the upper end of a plate 16 as shown, said plate being secured to the upper end of the extension leg 3 by screws or other appropriate fasteners. The inner ends of the guides 15 are beveled to form a pair of cam-like edges 17 which converge toward their upper ends and are here provided with notches or seats 18 for a purpose to be described.

A substantially V-shaped wire spring 19 is secured at the free ends of its arms to the bolts 12 as depicted most clearly in Figs. 2, 3 and 4, said arms abutting the cam-like edges 17 and serving to normally force the bolts 12 outwardly to hold their reduced ends 13 in engagement with the openings 14. When, however, the spring 19 is pulled upwardly, the converging cam-like edges 17

cause the two arms of said spring to move inwardly to withdraw both bolts, whereupon the extension leg 3 may be adjusted as required. When the spring is thrown 5 upwardly to its limit, the arms thereof will snap into the seats or notches 18 and thus the bolts will be held retracted while adjustment of the extension leg is being made.

From the foregoing, taken in connection with the accompanying drawing, it will be obvious that although the invention is of extremely simple and inexpensive nature, it will be highly efficient and positive in action, the device being applicable equally well to either leg of the ladder and since the socket 6, is of sufficient size, the device may be applied easily, even though the rounds 2 extend a slight distance beyond the outer sides of the legs, or if said sides be encumbered with other projections.

20 with other projections.
Since probably the best results are obtained from the specific construction shown, such construction constitutes the preferred form of the device, but I wish it understood, 25 however, that within the scope of the invention as claimed, numerous minor changes may be made without sacrificing the principal advantages.

I claim:

30 1. An extension leg combination for ladders comprising a channel-bar having at its lower end a socket adjacent its closed side to receive the lower end of the ladder leg, said socket having a bottom upon which said 35 ladder leg rests, the upper end of said bar having a vertical notch, a bolt passing through said notch and adapted for passage through said leg to secure the upper end of said bar in position, an extension leg 40 slidable in said channel-bar, and means for securing said extension leg in adjusted position.

2. An extension leg combination for ladders comprising a vertical channel-bar, 45 means for securing the upper end of said

Copies of this patent may be obtained for five cents each, by addressing the "Commissioner of Patents, Washington, D. C."

bar to a ladder leg, a band passing around the lower end of said bar and secured thereto, said band being spaced from the closed side of said bar and being formed on the lower edge with a flange extending toward said closed side, whereby a socket having a bottom is provided to receive the lower end of the ladder leg, an extension leg received slidably in said channel-bar and held against lateral displacement by said band, and means for securing said extension leg in adjusted position.

3. An extension leg combination for ladders comprising a vertical channel-shaped guide having vertically spaced openings in its side flanges, an extension leg slideable vertically in said guide, a pair of aligned tubular guides carried rigidly by said leg and having converging cam-like edges, cams at their inner ends, a pair of aligned bolts slideable in said tubular guides and adapted for reception in any of said openings, and a substantially V-shaped spring whose arms are secured to said bolts, said arms bearing against said cam-like edges. 70

4. An extension leg combination for ladders, comprising a channel bar and means for securing it to one of the ladder legs, both side flanges of said channel bar having vertically spaced openings, an extension leg 75 slidably received in the channel of said channel bar, and oppositely extending bolts mounted on said extension leg and receivable in said openings to hold said extension leg in vertically adjusted position, together with means for simultaneously projecting 80 both bolts.

In testimony whereof I have hereunto set my hand in the presence of two subscribing witnesses.

ABRAHAM E. DRUMMOND.
